ELECTRIC BATTERY LANTERN

Herbert J. Ashe, Stamford, Conn. (½ H. J. Ashe Co., Inc., P.O. Box 471, South Norwalk, Conn. 06852)

Filed Mar. 4, 1966, Ser. No. 1,291

Term of patent 14 years

(Cl. D48—24)

Fig. 4

Fig. 1

Fig. 2

Fig. 3

Fig. 5

FIGURE 1 is a top plan view of an electric battery lantern, embodying my new design;

FIGURE 2 is a side elevational view thereof;

FIGURE 3 is a bottom plan view thereof;

FIGURE 4 is an end elevational view thereof, and

FIGURE 5 is an elevational view of the end thereof opposite to the one shown in FIGURE 4.

The dominant features of my design reside in the portions shown in full lines.

I claim:

The ornamental design for an electric battery lantern, substantially as shown and described.
